UNITED STATES PATENT OFFICE.

JEAN CUYPERS, OF UERDINGEN-ON-THE-RHINE, GERMANY.

DRUM FOR DRYING MATERIALS.

Application filed July 16, 1926, Serial No. 122,937, and in Germany July 20, 1925.

My invention provides a rotary drying drum with improved internal distributing devices or carriers for the material to be dried, said carriers being arranged substantially parallel to the drum axis and each composed of three equally spaced radial arms with flanges extending therefrom. The carriers are grouped within the drum with their arms disposed in three series of parallel planes having a mutual angle of intersection of one hundred and twenty degrees.

Said arms, which are of equal length, may be bent up at the outer ends to form flanges pointing in the direction of rotation of the drum.

The special construction, method of operation and advantages of the invention are hereinafter set forth with reference to the typical example illustrated in the drawing 20 which represents a diagrammatic section through a drying drum in accordance with my invention.

Reference *c* denotes the drum, which is of sheet metal or other suitable material, and is 25 adapted to be rotated in the direction of the arrow *d*. Inside the drum *c* are disposed carriers *f* for the material, each of which, in cross section, has the form of a cross with three radial arms *g* provided, at their outer 30 edges, with flanges *i*. Other carriers *e* arranged round the inner wall of the drum are shaped differently as shown.

The centre of each cross is situated at the apices of three equilateral triangles; and the 35 arms *g* are disposed in rows along three series of parallel planes having a mutual angle of intersection of 120° , the arrangement being such that, in all the planes of each series, the arms point in the same direction 40 from their central axes. That is to say, all the arms *g* in the series of parallel vertical planes point downwards from their axes; all the arms *g* in the series of parallel planes that slope upwardly to the right point upwardly in that direction; and all the arms *g* in the series of parallel planes that extend 45 upwardly to the left point upwardly in that direction. At the same time, the sides of the equilateral triangles formed by the intersecting planes are double the length of the arms *g* of said crosses. This is represented in the 50 figure by the circle marked with the diameter $2k$. The advantage of this arrangement is that, in each of the parallel planes, each

arm *g* of the length *k* is always succeeded by 55 a gap of the same length.

The height of fall *h* of the material is that of a perpendicular drawn from the corner of a flange *i* to an arm of the adjacent cross.

During one revolution of the drum there 60 are three falls of material in each group of three carriers *f*, as indicated by the dotted lines. In the case of the marginal carriers there are, for the most part, only two falls.

Consequently, in the example shown, there 65 are altogether 108 falls during one revolution of the drum, a number considerably exceeding that occurring with any known distributing device of this kind for the same size of drum. The amount of material circulating in each group of adjacent carriers is no more than corresponds to the capacity 70 of one carrier trough *m*.

The figure clearly shows that, in each triangular group of carriers, out of the three 75 carrier troughs which face each other, only the one, *m*, which is facing upwards for the time being can contain material, because the flanges *i* are bent over so as to lead in the direction of rotation of the drum (arrow *d*). If this were not the case, then, with the drum rotating in the direction indicated, the material would not fall direct, as it should do, from the trough I—III of the carrier *a* into the trough I—II of the carrier *b* of the group 85 *a b a'*, but would fall past or along the arm *a* of that carrier to the trough I—III of the carrier *b'* of the group *a b b'*, and continue to do so until the arm *II* of the carrier *b* assumed the horizontal position.

The flanged shape of the arms *g* enables the groups to be advantageously disposed in triangular arrangement which increases the carrying capacity of the drum by comparison with known distributing devices.

Further, the invention affords the additional advantage that the carrying capacity of the trough is increased by the flanged shape of the carrier arms.

I claim:—

1. In a rotary drying drum, a plurality of carriers for the material to be dried arranged substantially parallel to the drum axis, each of said carriers comprising three radial arms substantially one hundred and twenty degrees apart, and flanges extending from the arms in the direction of rotation of the drum.
2. In a rotary drying drum, a plurality of

carriers for the material to be dried each constituted by three equally spaced radial arms with flanges extending therefrom in the same circular direction, said carriers being
5 arranged substantially parallel to the drum axis with their arms so disposed in rows in three series of parallel planes intersecting at

a mutual angle of one hundred and twenty degrees that the arms in all the planes of each series point in the same direction from 10 their central axes.

In testimony whereof I have signed my name.

JEAN CUYPERS.
